UNITED STATES PATENT OFFICE.

MATTHEW T. CHAPMAN, OF AURORA, ILLINOIS, ASSIGNOR TO THE AMERICAN WELL WORKS, OF AURORA, ILLINOIS, A CORPORATION OF ILLINOIS.

WELL-SINKING APPARATUS.

1,322,540.

Specification of Letters Patent. Patented Nov. 25, 1919.

Original application filed April 14, 1913, Serial No. 761,006. Divided and application filed May 18, 1914, Serial No. 839,381. Divided and this application filed August 13, 1917. Serial No. 185,911.

To all whom it may concern:

Be it known that I, MATTHEW T. CHAPMAN, a citizen of the United States, residing at Aurora, in the county of Kane, State 5 of Illinois, have invented certain new and useful Improvements in Well-Sinking Apparatus, of which the following is a specification, reference being had to the accompanying drawings.

10 This invention relates to well sinking apparatus of the type shown in Letters Patent 1,104,409, granted July 21, 1914, upon my application 761,006 and shown subsequently in my divisional application 839,381, filed 15 May 18, 1914, upon which Letters Patent, No. 1,248,614, dated December 4, 1917, has been issued, my present application being filed as a division of said application 839,381. It is one of the objects of my in-

20 vention to provide a new and improved form and arrangement of drilling apparatus especially adapted for boring through hard strata and adapted by reason of its form and action to retain its efficiency for a com- 25 paratively very long period. To this end, it is one of the principal objects of my invention to provide a construction and arrangement comprising a drill of comparatively large size and means for manipulat- 30 ing such drill in the hole being bored so as to cause the drill to dig into the bottom and the walls of the hole by a succession of heavy blows rather than by a grinding process. It is another object of my in- 35 vention to improve devices of this type in sundry details hereinafter pointed out. The preferred means by which I have accom- plished my several objects are illustrated in the drawings and are hereinafter specifi- 40 cally described. That which I believe to be new and desire to cover by this application is set forth in the claim.

In the drawings:

45 Figure 1 is a side view, partly in vertical section, of my improved drilling apparatus in position in the bottom of a hole being bored;

Fig. 2 is a bottom view of the drill shown in Fig. 1;

50 Fig. 3 is a horizontal section taken on line 3-3 of Fig. 1; and

Fig. 4 is a vertical central section taken substantially on line 4-4 of Fig. 1.

Referring to the several figures of the

drawings, in which corresponding parts are indicated by the same reference characters, 10 indicates a boring pipe having a coupling sleeve 11 mounted thereon by means of screw-threads, said coupling sleeve serving to connect a bracket 12 to said boring pipe 60 through the medium of a screw-threaded lug 13 formed with said bracket. A second bracket 14 is secured in position below the bracket 12 by means of suitable screws or bolts passing through arms 15 extending laterally from the brackets 12-14. In the construction shown, the screws or bolts also revolubly support cylindrical rollers 16 which serve as reamers, as hereinafter described. It will be understood that the 70 brackets 12-14 may be secured together in any other suitable manner as may be desired.

The bracket 14 terminates at its lower end in a cylindrical stud 17 extending at an angle relative to the boring pipe 10, in the construction shown this angle being approximately 45 degrees. Upon the stud 17 is revolubly mounted a drill 18 which is kept in position on the stud by means of pins 19 ex- 75 tending through suitable openings in the drill and working in a groove 20 extending circumferentially about the stud 17.

The lug 13 of the bracket 12 is provided with a centrally-located longitudinally-ex- 80 tending duct 21 communicating with the hollow boring pipe 10 and connecting at its lower end with a similar duct 22 extending down through the bracket 14 to the lower end of the stud 17. The drill 18, in turn, is provided with a central duct 23 communicating with the lower end of the duct 22. By this construction, water or other fluid forced downward through the boring pipe 10 has a free outlet through the opening 23 85 directly into the bottom of the hole being bored, such water being adapted to rise and thus remove from the hole the particles of rock or other material broken loose from the walls of the hole during the boring opera- 90 tion, all as is well understood in the art. Openings 24 are also provided through the drill 18 for facilitating the circulation of the water in and about the hole and the drill rapidly changing position therein.

100 As will be seen by an inspection of the drawings, the rollers or reamers 16 are serrated or toothed on their outer faces, serv-

ing thus the double function of holding the drill 18 in central position relative to the hole being bored and of smoothing off any irregularities in the side walls of the hole.

5 The function of holding the drill in central position in the hole being bored is of very considerable importance under certain circumstances and particularly when the drill is passing through a soft stratum into a hard 10 one or from a hard stratum into a soft one. Under such circumstances, a drill has a strong tendency to shoot toward the side at which the resistance happens to be smaller than at the other side by reason of an angular disposition of the strata or some irregularity in the conformation. It is therefore important that means be provided so far as possible for holding the drill in central position at such times.

15 20 As is seen by an inspection of Figs. 1 and 2, the drill is serrated, knurled, chiseled, or toothed over its entire bottom face and about its periphery, being preferably cast in this form of manganese steel or other very hard 25 and tough metal. The drill of course is free to rotate relative to the boring pipe 10 except as the action of the drill is controlled by its engagement with the walls of the hole being bored. By reason of the angular dis- 30 position of the stud 17 relative to the boring pipe 10, my improved drill, held in central position in the hole by the rollers or reamers 16, is given a continuously-progressive tipping movement or gyration as distin- 35 guished from a normal rotary movement, the drill being thus adapted to dig into the wall and the bottom of the hole rather than to grind off the surfaces. When the boring pipe is given a rapid rotation, the drill is 40 brought into contact with the walls of the hole with a succession of rapid heavy blows, there being sufficient vibration of the drill to insure a succession of blows in lieu of a smooth rolling contact. The drill is thus 45 adapted to break loose particles from the wall, which are then crushed by succeeding blows of the drill and then floated upward on the stream of water passing upward along the hole. The particles of rock so 50 broken loose and then crushed serve a useful function in the boring operation, being forced more or less into the walls of the hole and then again torn loose, other particles of matter being torn loose in the process.

By reason of this being accomplished by a 55 succession of heavy blows struck by a heavy drill, the wear upon the drill is very slight and it is very seldom necessary to remove the line of boring pipes from the well for the substitution of a fresh drill. 60

By my invention, I have provided a construction comprising a boring pipe and a drill revolvably connected therewith so as to revolve on an axis at an angle thereto, such connection being effected by the use of an 65 axle-member comprising the brackets 12-14. While I have shown rollers or reamers 16 in position upon the brackets 12-14 and prefer to employ such parts, it will be understood that I do not limit myself to this 70 particular construction except as herein-after specifically claimed, inasmuch as it is plain that an operative and efficient boring device is produced without the use of the reamers. So far as I am aware, I am the 75 first in the art to provide a boring mechanism of the type shown in the drawings, in which the axle-member, leaving out of consideration the reamers and other parts not necessary to an effective operation of the 80 mechanism, extends to a smaller distance laterally in every direction than does the drill mounted in a tipped position immediately below such axle-member, and my claim is to be construed accordingly. As 85 will be readily appreciated, if the rollers or reamers 16 are omitted, the drill would then probably not be held in centered position in the hole being bored, but the action of the drill would be substantially the same 90 except possibly that a larger hole would be produced.

What I claim as my invention and desire to secure by Letters Patent, is:—

In a well sinking apparatus, the combination of a boring pipe, a bracket fixedly connected therewith, a second bracket below said first-named bracket, means comprising vertically-extending bolts for connecting said two brackets fixedly together, a drill 95 revolvably connected with said second bracket and adapted to revolve about an axis at an angle to said boring pipe, and rollers revolvably mounted on said bolts adapted to hold said drill in substantially centered position 100 in the hole being bored. 105

MATTHEW T. CHAPMAN.
